DISPLAY RACK FOR CLOTHING OR LIKE ARTICLES

Theodore Sobel and Arthur Goldstein, Scarsdale, N.Y., assignors to Butler Industries, Inc., Newark, N.J., a corporation of New York

Filed Mar. 9, 1962, Ser. No. 69,174

Term of patent 3½ years

(Cl. D80—10)

Fig. 1.

Fig. 2.

Fig. 3.

FIG. 1 is a perspective view of a display rack for clothing or like articles embodying our new design, it being understood that the perforated panel is continuous throughout the planes in the area indicated;

FIG. 2 is a rear elevational view thereof; and

FIG. 3 is a side elevational view thereof.

We claim:

The ornamental design for a display rack for clothing or like articles, as shown and described.
